CONTAINER

Raymond E. MacDonald, Westwood, Mass., assignor of one-half to Edwin M. Warwick, Walpole, Mass.

Original application August 21, 1939, Serial No. 291,146. Divided and this application March 13, 1940, Serial No. 323,786

1 Claim. (CL 229—2.5)

This application is a division of my patent application Serial No. 291,146, filed August 21, 1939.

This invention relates to a paper container made of paper pulp or the like.

The principal object of my invention is to provide a paper pulp container with an integral bottom and side structure so constituted that it will have the necessary consistency and firmness required to permanently maintain its shape and which will be practical for commercial use, and be suitable to hold liquids and solid foods. Another object is to provide such a container that can be manufactured at a low cost.

The foregoing and other objects which will appear as the nature of the invention is better understood, may be accomplished by a construction such as is disclosed by the drawing and specification. The nature of the invention is such as to render it susceptible to changes and modifications, and, therefore, I am not to be limited to said disclosure; but am entitled to all such changes therefrom as fall within the scope of my claim.

In the drawing:

Figure 1 is a front elevational view, partly broken away and partly in section, of a finished paper container. Figure 2 is a plan view of said container and Figure 3 is a bottom view thereof.

As illustrated, my finished container R has an integral bottom and side structure. Where the side structure M merges with the bottom structure N this intermediate portion U is preferably

arcuate in shape as shown in Figure 1 of the drawing. Said bottom structure N is thinner than said side structure M and thinner than said intermediate portion U, and this thinness preferably results from compacting the material of said bottom structure N so that it occupies less space than the material in said side structure M. For instance, said bottom structure N may be only $\frac{1}{2}$ inch thick while said side structure M may be $\frac{1}{4}$ inch thick, thus providing a very firm and compact bottom, which constitutes the basic support of the remainder of the container as well as its contents.

When desired my container R may be fitted 15 with a metal liner L of aluminum or the like, or it may be plated or treated with some substance or chemical composition if desired, to render it waterproof.

The apparatus and method used in making my 20 container are the subject matter of my pending patent application Serial No. 291,146.

What I claim is:

25 A container made of paper pulp comprising an integral bottom and side structure, a portion of said structure extending arcuately between said top structure and said bottom structure, said bottom structure being thinner and the material forming it being more compacted than said side and arcuately extending structure, all of said bottom structure being flat and of a uniform thickness, and said side and arcuately extending structure being uniformly thick.

RAYMOND E. MACDONALD.
